UNITED STATES PATENT OFFICE.

ELMER G. MUNZ, OF DETROIT, MICHIGAN.

APPARATUS FOR IRRIGATING GOLF GREENS.

Application filed June 27, 1927. Serial No. 201,882.

This invention relates generally to irrigating apparatus and refers more particularly to apparatus for irrigating golf greens.

One of the primary objects of the invention 5 is to provide a system of piping for golf greens having at spaced intervals about the green, a plurality of adjustable connections to which a sprayer or the like may be attached for sprinkling different portions of the green.

10 Another object is to provide a specially constructed green cup having a sprayer head built therein, and adapted for attachment to any of the pipe connections of the irrigating apparatus.

15 With these and other objects in view, the invention resides in the novel features of construction and combination and arrangement of parts as more fully hereinafter set forth.

20 In the accompanying drawings:

Figure 1 is a diagrammatic view of the irrigating apparatus applied to a golf green;

Figure 2 is a section taken through the cup showing the spraying head and its connection 25 to one of the pipe ends;

Figure 3 is a plan view of the cup.

Figure 4 is a perspective view of the swinging joint.

Figure 5 is a modified form of the adjustable joint.

In the drawings wherein like characters of reference indicate like parts, the numeral 1 designates a golf green provided with a cup 2 shown in the present instance in Figure 1 35 as being placed in the center of the green. As is well known, it is preferable to move the cup about the green quite a few times during the playing season so as to prevent undue wear in the immediate vicinity of the cup.

40 Also, because of the short condition in which the grass must be kept great care must be taken in the upkeep of the green and it is very important that the same be constantly sprinkled to prevent the grass from being burnt, especially during midsummer. Usually ordinary surface sprinklers have been used where the water supply is convenient for use but at best this is a very unsatisfactory method as it entails the removing of the sprinklers 45 and hose before play may be started.

The present invention is designed to eliminate these objectionable features by first providing an underground system of water pipes and second, by providing cups with 50 built-in sprayer heads, capable of being moved to different portions about the green

for attachment at different points in the system.

As shown the numeral 3 indicates a main water supply pipe provided with a plurality 60 of branch pipes 4 extending in all directions so as to completely encompass the area covered by the green.

At the termination of each branch there is preferably provided an upstanding section 65 of pipe 5 having its end portion screw-threaded for engagement with the screw-threaded aperture 6 located in the bottom 7 of the cup 2.

As will be noted, this cup is of the usual size and form except that the flag holder 8 70 is placed at one side of the bottom of the cup. This holder merely consists of an open socket, the arrangement being such that any dirt collecting in the socket is simply packed down below the bottom of the cup.

75 Slidably mounted in the cup bottom 7 is a sprayer head 9 which in its raised operative position is adapted to extend above the cup rim. This is clearly shown in the full line position in Figure 2, while the lower inoperative position is shown in dotted lines of the same figure. The extreme lower portion of this head is enlarged as at 10 so as to prevent the removal thereof from the cup and also to provide a snug fit with the inwardly rounded 80 portion 11 of the aperture 6.

85 Any suitable type of sprayer may be used except that it is preferable that the extreme top end portion 12 be perfectly flat so that when the head is in its lower position this flat 90 top will seat in the enlarged portion 13 of the aperture 6 and thus provide a smooth surface for the bottom of the cup.

In order to allow for the adjustment of the cup when changing the same from one position to another, each section 5 is preferably 95 connected to its branch pipe 4 by means of a swinging joint 14. This joint preferably consists of a pair of elbows 15 and 16 connecting the branch 4 and section 5 respectively and having extending therefrom short sections 17 and 18 which are in turn connected by means of an elbow 19. With this arrangement a universal movement of the cup is allowed after it is attached to the section 5 so 105 that it may be adjusted to the proper height and position.

If desirable, however, other means such as that shown in Figure 5 may be provided. In this modification the section 5 is slidably 110 mounted in the fitting 20, this fitting consisting of the enlarged casing 21, having the in-

turned annular flange 22 from which projects the sleeve portion 23. Suitable packing 24 is placed between this sleeve and the section 5 while a split ring 25 surrounds the section 5 above the packing. A collar 26 is provided for screw-threadedly engaging the sleeve 23 and is adapted to compress the ring 24 against the packing and section 5 for forming a tight fit after the cup has been adjusted to its proper position.

It will of course be understood that when the apparatus is completely installed, all of the piping is entirely below the ground line of the green and that the sections 5 are adapted to extend substantially to the point indicated in Figure 2 so that when the cup is connected thereto the rim of the cup will be flush with the surface of the ground.

When it is desired to change the position of the cup all that is necessary is to unscrew the bottom of the cup from the section 5 to which it is connected and then move the cup and spray head to the desired position above one of the other pipe sections, whereupon it may be easily connected thereto by removing the required quantity of turf from above the pipe section in any suitable manner. When the water is turned on the force thereof will instantly move the sprayer head from its lower to its upper operative position and likewise after the green has been sufficiently sprinkled, the head will drop down to its inoperative position when the water is cut off. It will of course be understood that all of the pipe sections except the one to which the cup is connected will be plugged when not in use.

From the foregoing it is apparent that I have not only provided an irrigating apparatus for a golf green located substantially below the ground line of the green but have also provided a novel form of cup within which is built the sprayer head for the irrigating apparatus.

What I claim as my invention is:

- 45 1. In combination, a cup adapted for use upon golf greens and a sprayer head movably arranged within said cup and adapted to be moved to a position for permitting the cup to be used for the playing of golf.
- 50 2. In combination, a cup adapted for use upon golf greens and a sprayer head carried by and slidably mounted within said cup and adapted when in its inoperative position, to permit the use of said cup for the purpose intended.
- 55 3. In combination, a cup adapted for use upon golf greens having a bottom portion provided with an opening and a sprayer head slidably mounted in said opening and adapted when in its inoperative position, to permit the use of said cup for the purpose intended.
- 60 4. In combination, a cup adapted for use upon golf greens having a bottom portion provided with an opening and a sprayer head

slidably mounted in said opening, and having its top portion arranged to form a portion of the cup bottom when the head is in its lower inoperative position.

5. In combination, a cup adapted for use upon golf greens having a bottom portion provided with an opening therethrough, and having its upper surface surrounding said opening recessed, and a sprayer head slidably mounted in said opening and having a flat upper portion adapted to seat in said recess in the lower position of said head whereby the top surface of said flat upper portion will form a portion of said cup bottom.

6. In an irrigation apparatus for golf greens, a pipe line having a plurality of branch pipes located at spaced intervals about the green below the surface thereof, a cup for said green adapted for attachment to one of said branch pipes and a sprayer head movably mounted in said cup for engagement with said branch pipe, said head being adapted when in its inoperative position, to permit the use of said cup for the purpose intended.

7. In an irrigation apparatus for golf greens, a pipe line having a plurality of branch pipes located at spaced intervals about the green below the surface thereof, a cup for said green having a bottom portion provided with an opening adapted to register with one of said branch pipes and a sprayer head carried by said cup and having an elongated body portion slidably mounted in said opening and arranged to lie within said branch pipe in its lower inoperative position whereby said cup may be utilized for the purpose intended.

8. In an irrigation apparatus for golf greens, a pipe line having a plurality of branch pipes located at spaced intervals about the green below the surface thereof, a cup for said green secured to one of said branch pipes, a sprayer head mounted in said cup for engagement with said branch pipe, and adjustable means connecting said branch pipe to said pipe line whereby a correct positioning of said cup relative to the surface of the green may be obtained.

9. In combination, a cup adapted for use upon golf greens having a bottom portion provided with a centrally disposed opening, a sprayer-head slidably mounted in said opening, the bottom portion of said cup being provided with a second opening adjacent the wall of said cup and constituting a flag holder for said cup.

10. In combination, a cup adapted for use upon golf greens, and spraying means carried by said cup and so arranged with respect thereto as to permit the use of said cup for the purpose intended.

In testimony whereof I affix my signature.

ELMER G. MUNZ.
